(57) **CLAIM**

The ornamental design for a light emitting diode module, as shown and described.

DESCRIPTION

FIG. 1 is a perspective view of a light emitting diode module showing the new design;

FIG. 2 is a front view thereof;

FIG. 3 is a rear view thereof;

FIG. 4 is a right side view thereof; and,

FIG. 5 is a top view thereof.

A left side view and a bottom view of the light emitting diode module are omitted since the left side view and the bottom view are respectively symmetrical with the right side view and the top view.
